Inventor
B. Hatley

By Franklin W. Haigh

Attorney

UNITED STATES PATENT OFFICE.

BIRD HATLEY, OF EVERSON, WASHINGTON.

WOOD-SAW.

1,374,736.

Specification of Letters Patent. Patented Apr. 12, 1921.

Application filed March 22, 1920. Serial No. 367,825.

To all whom it may concern:

Be it known that I, BIRD HATLEY, a citizen of the United States, residing at Ever-
son, in the county of Whatcom and State
5 of Washington, have invented certain new
and useful Improvements in Wood-Saws;
and I do hereby declare the following to
be a full, clear, and exact description of the
invention, such as will enable others skilled

10 in the art to which it appertains to make
and use the same, reference being had to the
accompanying drawings, and to the letters
and figures of reference marked thereon,
which form a part of this specification.

15 The principal object of this invention is
to provide a novel wood sawing machine of
the type in which the rotary knife or saw
is moved bodily in a rectilinear path trans-
versely of a stationary log or timber being
20 operated upon.

A further object of this invention is to
provide a novel means, manually controlled,
for reversing the path of movement of the
saw, if for instance, the saw strikes a nail
25 or the like in the wood being sawed and it
is desired to disengage the saw from such
obstruction.

The invention has for its object certain
improvements in details, going to make up
30 the ultimate perfection of the machine as
an entirety.

The accompanying drawings clearly dis-
close an exemplary form of the underlying
principles of my invention.

35 Briefly described:

Figure 1 is a view in side elevation of the
machine.

Fig. 2 is a top plan view.

Fig. 3 is a view in end elevation looking
40 at the right hand end of Fig. 1, and

Fig. 4 is a detached detail view in per-
spective of the mechanism for effecting the
reversal of the direction of movement of
the saw.

45 Referring now in detail to the drawings:

The operating parts of my machine are
mounted upon a suitable base, herein shown
as comprising parallel bars 1, 1, and bars
2, 2 secured at one end thereof near one
50 end of the bars 1, 1 and disposed at an
angle to the latter. All of said bars may
rest upon and be secured to transversely dis-
posed bars 3, 3.

Disposed at one end of said bars 1, 1 and
55 2, 2 is a platform 4. Adapted to be de-
tachably connected to said platform at one

end thereof is a runway comprising, as
shown, the side members 5, 5, the stationary
cross-pieces 6 and the rollers 7, the latter
being suitably supported in bearings 8 on 60
the side members 5, 5.

The platform 4 is provided with a trans-
versely extending slot 9 disposed directly
beneath the saw 10, whereby sawdust may
escape. 65

Secured at the other end of the bars 1, 1
are upright standards 11, 11, carrying at
their tops bearings 12, 12, in which is ro-
tatably supported a shaft 13. Said shaft
carries at one end a pulley 14, around which 70
may pass a belt, not shown, passing around
another pulley on a drive shaft, constitut-
ing the power shaft. Also carried by the
shaft 13, toward the end thereof carrying
the pulley 14, is a second pulley 15 around 75
which, and around a second pulley 16 on
a shaft 17 at the other end of the machine,
passes a belt 18.

The shaft 17 is rotatably supported in
bearings 19, 19 carried upon blocks 20, 20, 80
secured to timbers 21, 21 rising from the
base bars 2, 2, as shown most clearly in
Fig. 1.

The saw 10 is fixed on a shaft 22 rotatably
supported in a boss or bearing 23 at the 85
lower end of a swinging bracket 24, pro-
vided at its upper end with a yoke 25 piv-
otally suspended upon the shaft 17.

Carried by one end of the shaft 22 is a
pulley 26 around which, and around a pulley 90
27, fast on the shaft 17, is a driving belt 28.

It will thus be seen that the movement
of the pulley will be imparted through the
shaft 13 to the pulley 15, thence through the
belt 18 to the pulley 16, thence through the 95
shaft 17 to the pulley 27, and thence through
the belt 28 to the pulley 26 on the shaft
22 carrying the saw 10, which latter is there-
by rotated.

On the end of the shaft 13, opposite the 100
pulley 14, is a sprocket wheel 29, meshing
with a sprocket chain 30 passing around a
second sprocket wheel 31 on a shaft 32 ro-
tatably supported in bearings 33, 33 on ver-
tically disposed plates 34, 34, provided with 105
lateral feet 35, 35, through which, and
through timbers 36, 36 disposed upon the
bars 1, 1 and 2, 2 transversely thereof, pass
securing bolts 37.

Fast on the shaft 32 is a gear wheel 38 110
meshing with a pinion 39 on a shaft 40
rotatably supported in bearings carried by

the side plates 34, 34. Said pinion meshes with a second pinion 41 on a shaft 42, also rotatably supported in bearings carried by the side plates 34, 34. Said pinion 41 meshes with a gear wheel 43 carried by a shaft 44 rotatably supported in bearings upon the side plates 34, 34. Said train of gears, just described, is disposed adjacent one of the side plates 34, as shown most clearly in Fig. 2.

Rotatably supported in the plates 34, 34, intermediate the top and bottom thereof, is a shaft 45, fast on which is a friction wheel 46 adapted to frictionally engage either one of two friction pinions 47, 48, rotatably carried on stub shafts 49, 49, carried by a rocker arm 50 pivoted at its lower end, as shown at 51, on the shaft 45. At its upper end said rocker arm is articulated, as shown at 52, with one end of an operating member 53 extending toward the saw 10, as shown in Fig. 1, so as to be within convenient reach of the operator standing near the saw.

Fast on the shaft 32 is a friction wheel 54, and fast on the shaft 44 is a similar friction wheel 55, said friction wheels 54 and 55 being in the path of travel of the friction pinions 47 and 48 as the same are bodily swung by means of the rocker arm 50 controlled by the operating member 53.

Fast on one end of the shaft 45 is a crank 56 pivotally secured at its end, as shown at 57, to one end of a link 58, the other end of which is pivotally secured, as shown at 59, to a rocker bar 60, pivoted at its lower end, as shown at 61, to one of the base bars 1. At its upper end said rocker bar 60 is pivotally connected, as shown at 62, to one end of a link 63 pivotally secured, as at 64, at its other end to the swinging bracket 24 carrying the saw 10. Said bracket 24 is provided with two or more apertures 65, so that the end of the link 63 may be adjustably secured in any one of said apertures.

The operating handle 53 is provided on its under surface with a plurality of notches 66, any one of which may be engaged with a pin 67 carried by one of the frame uprights 21, whereby the handle may be held against movement.

Pivotally secured to the operating handle 53 between the ends thereof, as shown at 68, is one end of a link 69, pivotally secured at its other end, as shown at 70, to a brake beam or arm 71 fulcrumed intermediate its ends, as shown at 72, to one of the side plates 34, and carrying at its free end a brake shoe 73 adapted to be brought into frictional contact with the friction wheel 46 to stop the movement thereof when the operating handle 53 is moved into neutral position so that the friction wheels 47 and 48 are out of contact with the friction wheels 54 and 55. To effect this braking action, the operating handle 53 is disengaged from

the pin 67 and is pushed so as to shift the rocker arm 50 so as to disengage the friction pinions 47 and 48, and simultaneously the operating handle 53 is shoved downward so as to rock the brake arm 71 on its fulcrum 72 and throw the brake shoe 73 into frictional contact with the friction disk 46.

Should the saw 10 strike an obstruction, such as a nail, in the board or log being sawed, it is desirable to reverse the rectilinear path of movement of the saw, so as to disengage the same from said obstruction. Obviously, this reversal is accomplished by tilting the rocker arm 50 on its pivot 51, so as to shift the friction pinion 47 out of engagement with the friction disk or wheel 54, and the friction pinion 48 into engagement with the friction disk or wheel 55.

What I claim to be new is:

1. In a wood sawing machine, the combination of a rotatable saw, and mechanism for bodily moving the same along a curvilinear path, comprising a rotatable crank shaft, connections between said crank shaft and said saw, a friction wheel fast on said crank shaft, a train of gearing, means for rotating said gear train, two friction disks rotating with said gear train, and two friction pinions disposed between said friction disks and being bodily shiftable to bring either one into frictional contact with the adjacent friction disk and with said friction wheel.

2. In a wood sawing machine, the combination of a rotatable saw, and mechanism for bodily moving the same along a curvilinear path, comprising a rotatable crank shaft, connections between said crank shaft and said saw, a friction wheel fast on said crank shaft, a train of gearing, means for rotating said gear train, two friction disks rotating with said gear train, and two friction pinions disposed between said friction disks and being bodily shiftable to bring either one into frictional contact with the adjacent friction disk and with said friction wheel, and means for causing said shifting of the pinions, including a rocker arm carrying said pinons.

3. In a wood sawing machine, the combination of a rotatable saw, and mechanism for bodily moving the same along a curvilinear path, comprising a rotatable crank shaft, connections between said crank shaft and said saw, a friction wheel fast on said crank shaft, a train of gearing, means for rotating said gear train, two friction disks rotating with said gear train, and two friction pinions disposed between said friction disks and being bodily shiftable to bring either one into frictional contact with the adjacent friction disk and with said friction wheel, and means for causing said shifting of the pinions, including a rocker arm car-

rying said pinions, and an operating member pivoted to said rocker arm.

4. In a wood sawing machine, the combination of a rotatable saw, and mechanism for bodily moving the same along a curvilinear path, comprising a rotatable crank shaft, connections between said crank shaft and said saw, a friction wheel fast on said crank shaft, a train of gearing, means for 10 rotating said gear train, two friction disks rotating with said gear train, and two friction pinions disposed between said friction disks and being bodily shiftable to bring either one into frictional contact with the 15 adjacent friction disk and with said friction wheel, and means for causing said shifting of the pinions, including a rocker arm carrying said pinions, means for moving said rocker arm to shift said pinions to an intermediate position where said pinions are out 20 of contact with both of said friction disks, and means controlled by said rocker-arm operating means for braking said friction wheel.

25 5. In a wood sawing machine, the com-

bination of a rotatable saw, and mechanism for bodily moving the same along a curvilinear path, comprising a rotatable crank shaft, connections between said crank shaft and said saw, a friction wheel fast on said 30 crank shaft, a train of gearing, means for rotating said gear train, two friction disks rotating with said gear train, and two friction pinions disposed between said friction disks and being bodily shiftable to bring 35 either one into frictional contact with the adjacent friction disk and with said friction wheel, and means for causing said shifting of the pinions, including a rocker arm carrying said pinions, an operating member 40 pivoted to said rocker arm for throwing the same to shift said pinion to an intermediate position where said pinions are out of contact with both of said friction disks, and means controlled by a downward movement 45 of said operating member for braking said friction wheel.

In testimony whereof I hereunto affix my signature.

BIRD HATLEY.
